UNITED STATES PATENT OFFICE

121,889

DESIGN FOR A FILM WINDER

Walter W. Boes, Dayton, Ohio

Application May 18, 1940, Serial No. 92,462

Term of patent 7 years

To all whom it may concern:

Be it known that I, Walter W. Boes, a citizen of the United States, residing in Dayton, in the county of Montgomery and State of Ohio, have invented a new, original, and ornamental Design for a Film Winder, of which the following is a specification, reference being had to the accompanying drawing, forming part thereof.

Fig. 1 is a top plan view of a film winder show-

ing my new design, the numerals being merely representative;

Fig. 2 is a front elevational view; and

Fig. 3 is a right end elevational view of the same.

I claim:

The ornamental design for a film winder, substantially as shown and described.

WALTER W. BOES.
